P. G. F. SCHUBERT

CONTAINER, ESPECIALLY CANISTER, FOR AUTOMOBILE DRIVING LIQUIDS

Filed Sept. 24, 1925

Fig. 1.

Fig. 2.

UNITED STATES PATENT OFFICE.

PAUL GUSTAV FRANZ SCHUBERT, OF DRESDEN, GERMANY.

CONTAINER, ESPECIALLY CANISTER, FOR AUTOMOBILE DRIVING LIQUIDS.

Application filed September 24, 1925, Serial No. 58,389, and in Germany April 4, 1925.

The present invention has for its object to provide an improved form of container, more particularly a canister for automobile driving liquids, as gasoline, oil or the like. A novel feature of said container or canister is its unsymmetrical conically rounded cover. An aperture for filling and discharging the liquid is provided on the steeply sloping part of this cover. A vent tube adapted to 10 permit air to pass in or out of the container or canister has one of its extremities connected to the upper part of the aperture for filling and discharging the liquid, said tube extending in a slanting direction to the opposite part of the canister cover. Adjacent the other end of said tube is provided an opening for the passage of air, said opening being at a point higher than the lower edge of the filling and discharge aperture. Thus, 15 since the container or canister can not be filled higher than the lower edge of its filling aperture, it is evident that the inner opening of the vent tube will always be above the level of the liquid, that is, in the air space which will always normally exist within the top of the canister.

When the canister is used for the discharge of oil, air is continuously admitted into the interior of the container through 20 the vent tube connected near the upper part of the discharge aperture, so that a gurgling and bubbling of the oil during its discharge is prevented.

In case the oil has entered the vent tube 25 during the conveyance of the canister, the oil would, at the beginning of its discharge, be drawn off from the vent tube into the interior of the canister by the vacuum created or produced in the interior of the canister, and in consequence said vent tube would 30 constantly be open so that the air could always enter into the canister.

Experiments have proved that even the heaviest oil can be discharged from the canister forming the object of the present invention within the shortest time, so, for instance, 2 1/4 lbs. (equal to 5 kilograms) of heaviest oil were discharged within 30 seconds. With the use of the canisters known 35 up to the present, 4 minutes at least were necessary for said discharge.

The object of the present invention is represented in one example of construction in the drawing annexed to the description.

Fig. 1 is a longitudinal elevation, partly in section, and Fig. 2 a front elevation of the

container or canister. Fig. 3 represents in longitudinal section the upper part of a modification of the container and Fig. 4 a section taken through the line A—B of Fig. 60 3. Figs. 5 and 6 represent similarly details of a further modification of the container shown in Figs. 3 and 4.

As seen from the drawing, *b* is the container or canister, *a* its cover of an unsymmetrical and conically rounded shape and *e* the filling and discharging aperture arranged in the steeply sloping part of the cover mentioned. *c* is a head surrounding the aperture *e* and arranged for the discharge of the liquid. *d* is a hollow or solid stopper provided on its outer surface with a thread to be screwed into the head *c*. *f* is an opening arranged in the upper edge of the aperture *e* provided in the rounded cover *a*, said opening being in connexion with one end of the interior vent tube *g*. Said tube extends in a slanting direction towards the opposite part of the cover *a* and is provided near its other extremity with an 80 opening *h* for the admission and issue of air in such a manner that said opening is situated within the air-chamber below the cover and at a higher level than the lower-edge of the admission and discharge-opening *e*.

In the modification of the container or canister shown in Figs. 3 and 4, the stopper *d'* screwed into the head *c* is formed as a carrier for the discharge-spout *k* and a passage *i* is arranged in its bottom.

The small opening *f* arranged within the unsymmetrical conical part of the cover *a* is, for the purpose of discharging or emptying and filling the container or canister, brought in free connection with the opening *i* of the stopper *d'* when screwed into the head *c*. When the canister is not in dispensing use the stopper *d'* is turned so as to bring the opening *i* out of register with the opening *f*, as illustrated in Fig. 4.

Fig. 5 represents in longitudinal section and Fig. 6 in transverse section to line C—D another modification of the stopper carrying the spout *k*. According to this modification 105 the opening *f* in the bottom of the head *c* and the opening *i* in the bottom of the stopper *d* are maintained, but a second opening *i'* is provided, diametrically opposite the said opening *i* within the stopper-bottom. When the spout *k* is in position suitable to discharge the canister the opening *i* is situated 110

in front of the opening *f* and air can enter through both openings and through the vent tube *g* into the air-chamber within the cover *a*.

5 If however the stopper *d'* together with the spout *k* is turned into a position suitable for filling the canister (Fig. 5) the opening *i'* is adjusted in front of the opening *f*, so that during the filling of the canister the 10 air can issue outwardly by the tube *g*.

In case the canister is not in use, the stopper *d'* with the spout *k* may be removed by unscrewing it from the head *c* and the apertures *e* and *f* in the wall of the cover *a* may 15 then be closed by a stopper *d*, as shown in Fig. 1.

What I claim is:

1. A container of the character described comprising, an unsymmetrical conically 20 rounded cover, a filling and discharge aperture in the more steeply sloping side thereof and a vent tube within said cover, said tube having an open end adjacent the upper edge of the filling and discharge aperture, 25 extending in a downwardly slanting direc-

tion toward the opposite side of the cover and being provided near its other end with an air inlet and outlet opening, said opening being at a level higher than the lower edge of the filling and discharge aperture. 30

2. A container of the character described comprising, an unsymmetrical conically rounded cover, a filling and discharge aperture in the more steeply sloping side thereof, a vent tube within said cover and connected with an opening adjacent said filling and discharge aperture, and a stopper adapted to be applied to the aperture, said stopper being traversed by a discharge spout and provided with a pair of oppositely disposed openings arranged to coincide alternately with the opening at the end of the vent tube, the one during the filling of the container and the other during the discharge thereof. 35

In testimony that I claim the foregoing as my invention, I have signed my name this 10th day of September, 1925.

PAUL GUSTAV FRANZ SCHUBERT.
